UNITED STATES PATENT OFFICE.

FRANK KALISTA, OF STEINWAY, NEW YORK.

GAME.

1,238,522.

Specification of Letters Patent. Patented Aug. 28, 1917.

Application filed January 22, 1917. Serial No. 143,632.

To all whom it may concern:

Be it known that I, FRANK KALISTA, a citizen of the United States, residing at Steinway, Long Island, in the county of 5 Queens and State of New York, have invented certain new and useful Improvements in Games, of which the following is a full, clear, and exact specification.

This invention relates to a game to be 10 known as Rollout, and has for its object to provide a game apparatus including a board having a series of indicia bearing spaces, a corresponding number of disks to fit over said spaces and cover the indicia thereon, 15 and a chance controlled play indicating means to determine which of the spaces are to be covered. The game apparatus may also include a score card or sheet to be used in connection with the game as will be here- 20 inafter explained.

The invention will be first hereinafter described in connection with the accompanying drawings which constitute part of this specification, and then more specifically defined 25 in the claims at the end of the description.

In the accompanying drawings, wherein similar reference characters are used to designate corresponding parts throughout the several views.

30 Figure 1 is a plan view of a board to be used with my improved game.

Fig. 2 is a collective view of one set of disks such as are used by each player.

35 Fig. 3 is a view of the preferred form of chance controlled play indicator, comprising two dice and a cup, and

Fig. 4 is a plan view of a score card or sheet, for use with the game.

The board 1 is preferably made rectangular but its shape and dimensions may be varied if desired. On the upper surface of the board a plurality of series of spaces 2 are indicated, said spaces being preferably round as illustrated. Six groups or series of 40 spaces are marked on the board illustrated in Fig. 1 and are distinguished from each other by the letters A, B, C, D, E and F. The board is thus adapted for use by any number of players up to six. Each of the 45 groups or series of spaces 2 bear progressive indicia, preferably the numerals 2 to 12, there being eleven spaces in each group or series.

The game apparatus includes a set of eleven disks 3, Fig. 2, corresponding to each 55 group or series of spaces 2, so that where the board bears six groups of said spaces, there should be six corresponding groups of eleven disks each as illustrated in Fig. 2. If desired, each group of disks 3 may be made 60 a distinctive color, and the corresponding group of spaces 2 on the board may be similarly colored to prevent confusion.

In playing the game, two dice 4 and dice cup 5, Fig. 3, and a score card 6, Fig. 4, or 65 other sheet of paper, are used. The players roll out the dice in turn and cover the spaces in their respective groups bearing indicia corresponding to the numbers shown on the dice with the disks 3. When a player rolls 70 out a number which has already been covered by him, the next player is entitled to cover the same number in his group of spaces, and if said next player has said space already covered, the next player after 75 him may cover this space, and so on. If a player rolls out a number which has already been covered by all the players, he must make a mark on the score card opposite the letter corresponding to his group of spaces. 80 When all of the spaces have been covered in any one group, the game is concluded, and the player having the fewest number of marks on the score card is the winner. For example, if six persons have been playing a 85 game and the score shown in Fig. 4 is the result, the player using the group of spaces D will be the winner because he has only one mark on the score card.

Having thus described my invention, what 90 I claim as new and desire to secure by Letters Patent of the United States is:

1. A game apparatus including a game board presenting a plurality of series of spaces, progressive indicia on said spaces, a 95 series of disks corresponding to each of said series of spaces and adapted to be arranged in superimposed relation on said spaces for covering the indicia thereon, and a chance controlled play indicator to determine which 100 particular space is to be covered by each player in turn.

2. A game apparatus including a game board presenting a plurality of series of spaces, progressive indicia on said spaces, 105 series of disks corresponding to the series of

spaces and adapted to be arranged in superimposed relation on said spaces for covering the indicia thereon, a chance controlled play indicator for determining which particular space is to be covered by each player in turn, and a score card for keeping a record of the times each player receives indicia on the

play indicator corresponding to spaces which have already been covered by all the players.

In testimony whereof I have signed my name to this specification. 13

FRANK KALISTA.
